UNITED STATES PATENT OFFICE.

JOSEPH H. CROSBY, OF JACKSONVILLE, FLORIDA, ASSIGNOR TO GREENLEAF & CROSBY COMPANY, OF FLORIDA.

DESIGN FOR A HANDLE FOR KNIVES OR SIMILAR ARTICLES.

SPECIFICATION forming part of Design No. 34,198, dated March 12, 1901.

Application filed February 16, 1901. Serial No. 47,706. Term of patent 7 years.

To all whom it may concern:

Be it known that I, JOSEPH H. CROSBY, a citizen of the United States, residing at Jacksonville, in the county of Duval and State of

Florida, have invented a certain new and original Design for the Handle of a Knife or Similar Article, of which the following is a specification, reference being had therein to the accompanying drawings.

Figure 1 is a side view of a knife-handle, showing my design; and Fig. 2, a sectional view taken on line $x x$ of Fig. 1.

As shown in the drawings, the leading or material feature of my design consists in the

representation of an alligator bearing the upper portion of the handle between his jaws.

In detail my design is as follows: The contour of the body portion of the handle is

formed by an alligator a , whose tail b is folded back upon the belly. The distended jaws $c c$ of the reptile is represented as encompassing the portion of the handle d adjacent to the blade. The portion d is longitudinally fluted.

It is apparent that this design is also applicable to forks and other similar articles.

Having described my invention, what I claim as new, and desire to secure by Letters Patent, is—

The design for a knife-handle or similar article, as herein shown and described.

In testimony whereof I have affixed my signature in presence of two witnesses.

JOSEPH H. CROSBY.

Witnesses:

THOMAS P. DURHAM,
HAYDEN W. CROSBY.
